PROPELLING DEVICE

Earl Houser Smith, Flushing, N. Y.

Application April 17, 1934, Serial No. 720,919

14 Claims. (Cl. 170—162)

This invention has general relation to propellers and, while not necessarily restricted to such use, the same is primarily concerned with propelling devices for air-craft.

Propellers for air-craft which have heretofore been in use, have lacked considerable in efficiency which is mainly attributed to the fact that the propeller blades follow in the wake of one another and create such a disturbance or turbulence as to seriously interfere with the propulsive force exerted, it being common knowledge that only the extreme outer ends or tip portions of the blades exert any appreciable propulsive force.

It is, therefore, an object of the present invention to provide an improved propeller in which this interference is materially overcome by so mounting and moving the blades with reference to each other that each blade throughout substantially its entire length acts upon an undisturbed medium to obtain a highly efficient propulsive force.

The invention more particularly comprehends a propelling device including a driven rotary hub and circumferentially spaced blades each of which protrudes from the hub in a generally radial direction with means for imparting movement to the blades so as to cause the same to respectively travel in conical paths, while moving bodily with the hub about its axis of rotation.

The invention further contemplates a propelling device of the indicated character which, due to its construction and arrangement, and the forward movement of the craft on which it is mounted, causes any selected point on the blades to travel in a succession of contiguous arcs while following a generally spiral path.

More specifically the invention embodies a driven rotary shaft, a hub secured to the shaft for rotation therewith, a gear concentric to and fixed with reference to the shaft and hub, circumferentially spaced blades protruding in a generally radial direction through the hub, an eccentric for each blade mounted to turn in the hub on radial axes perpendicular to the shaft and hub axes, and planetary gears meshing with the fixed gear and connected with the eccentrics for turning the same upon rotation of the shaft and hub.

The invention further resides in a propelling device of the indicated character which is not unduly complicated in its structure, which may be economically produced, which possesses the requisite strength and which is highly efficient for its intended purpose.

With the above recited and other objects in view, reference is now made to the following specification and accompanying drawings in which there has been illustrated by way of example a preferred embodiment of the invention, while the appended claims cover variations and modifications thereof which fall within their scope.

In the drawings:

Fig. 1 is a perspective view of a propeller constructed in accordance with the present invention.

Fig. 2 is a perspective view with the hub casing removed to disclose the gearing arrangement.

Fig. 3 is a longitudinal sectional view through the propeller taken approximately on the line 3—3 of Fig. 4.

Fig. 4 is a transverse sectional view therethrough taken approximately on the line 4—4 of Fig. 3.

Fig. 5 is a detail sectional view taken approximately on the line 5—5 of Fig. 4.

Referring to the drawings by characters of reference, 10 designates a driven rotary propeller shaft which extends through a fixed or non-rotary gear 11 and which gear has connected therewith an annulus 12 having an arcuate bearing concavity 13 on its outer face, the inner end portion of the annulus being mounted in a recess 14 formed in the outer end of the fixed gear 11 and being secured against rotation by splines 15.

The propeller further includes a sectional hub structure made up of inner and outer mating casing sections, which sections are generally designated by the reference characters 16 and 17, and which sections are secured together in any desired manner but as illustrated by way of example, the sections are provided with complementary flanges 18 and 19 through which bolts 20 extend. The hub structure comprises a hollow generally cylindrical central casing portion 21 having its axis concentric to the axis of the propeller shaft 10. The hub structure further includes a plurality of hollow cylindrical casing members 22, two being shown in the present instance, but it is to be understood that more than two may be employed within the scope of the invention. The casing members 22 in the embodiment shown have their axes disposed in alignment and on a line perpendicular to and intersecting the axis of the propeller shaft 10 and the axis of the hollow cylindrical central portion 21, the members 22 being in open communication at their inner ends with the central portion 21. The outer end wall 23 of the central portion 21 of the hub structure is provided with

an axial bore 24, through which the outer end of the propeller shaft 10 extends and with which it is connected for rotation therewith by splines or equivalent means 25 so that the hub is driven by and turned with the propeller shaft. The outer end of the shaft is threaded at 26 and a nut 27 is threadedly engaged therein. The inner face of the outer end wall 23 is formed with an arcuate bearing concavity 28 confronting the bearing concavity 13 of the annulus 12 and so located with reference thereto that the arcs of said concavities 13 and 28 are struck from a common center located at the intersection of the axes of the propeller shaft 10 and the axial line 11 passing through the members 22. The fixed gear 11 extends through an opening 29 in the rear end wall 30 of the central portion 21 of the hub structure and a suitable roller or anti-friction bearing 31 is interposed between the hub structure and the fixed gear at this point.

The arcuate bearing concavities 13 and 28 are of semi-spherical formation and have mounted therebetween for universal rocking movement, a spherical element or ball 32 which is provided with a bore 33 through which the propeller shaft 10 extends, the bore having a constricted central diameter 34 approximating the diameter of the propeller shaft 10 and the remaining opposite portions of the bore being of outwardly flared, frusto-conical formation and of increasing diameters towards the outer ends of the bore which open through the periphery of the ball or spherical element 32. The ball or spherical element 32 is provided with diametrical oppositely protruding integral arms 35 having concentric sockets 36 opening through the outer ends and extending inwardly therefrom. The propeller blades 37, which may be of any desired design, have shanks 38 at their inner ends, the terminals of which are fitted in the sockets 36 of the arms 35 and are secured therein by keys 39. The shanks 38 are each formed with a substantially spherical bearing 40 which is snugly fitted in an eccentric bearing opening 41 in a rotary eccentric disc 42 which is preferably split or made up of mating semi-circular sections 43 and 44 to facilitate the assembly thereof. The eccentric discs are secured within the outer ends of cylindrical sleeves 45 for turning movement therewith and are secured thereto by splines 46 or an equivalent keying arrangement. The cylindrical sleeves 45 extend partially into annular bosses 47 which protrude outwardly from the members 22 of the hub structure and the axes of said sleeves coincide with the axes of the members 22. Anti-friction bearings 48 are interposed between a portion of each sleeve 45 and each member 22. The innermost ends of the sleeves 45 are each formed or otherwise provided with a beveled gear 49, the teeth of which mesh with the beveled gear teeth 50 of the fixed gear 11 whereby upon rotation of the propeller shaft 10 and the hub structure with reference to the fixed gear 11, the gears 49 are caused to planet around the fixed gear 11 so that the sleeves 45, while moving bodily with the hub structure and propeller shaft 10, are caused to rotate on their own axes with reference to the hub. This relative rotation of the sleeves imparts through the medium of eccentric discs 42 a relative orbital movement of the propeller blades so that they travel in a substantially conical or gyratory path of movement. However, due to the bodily movement of 75 the blades about the hub, any selected point on

the blades will move in a succession of contiguous arcs, while due to the forward movement of the craft on which the propeller is mounted, the succession of contiguous arcs in which the blades are travelling will follow a generally spiral path. 5

The non-rotary gear 11 may be anchored in any desired manner to a fixed support but in the embodiment illustrated, the protruding rear end of the gear is secured by splines 51 to a flange 52 which in turn is bolted as at 53 to the nose 10 or forward end of the fuselage or to a motor casing or other equivalent support 54. In order to secure the gear and flange in assembled relation, the rear terminal of the gear 11 which protrudes from the flange 52 is externally threaded as at 15 55 and a lock nut 56 is applied thereto.

Due to this construction and arrangement, it will be apparent that one propeller blade 37 will follow a path further removed from the wake of the preceding blade than in propellers having 20 fixed radial blades, so as to be less affected by the turbulence or disturbance thereof and hence the blades will act upon a denser medium so as to impart a more effective or sufficient propulsive force than where the blades follow in the wake 25 of each other. Furthermore, due to the movement and action of the blades a substantially continuous and uniformly effective propelling thrust will be exerted throughout the entire cycle of movement of each blade. 30

What is claimed is:

1. A propelling device including a rotary driven shaft, a hub secured thereto, circumferentially spaced blades mounted on the hub and protruding in generally radial directions therefrom, and 35 coaxing means for imparting gyratory motion to the blades during the rotation of the shaft and hub so as to cause any point on each blade to travel in a succession of contiguous arcs and in a generally spiral path due to the combined 40 gyratory motion of the blades and the forward movement of the device.

2. A propelling device including a rotary driven shaft, a hub secured thereto, circumferentially spaced blades mounted on and protruding from 45 the hub in generally radial directions and coaxing means on the hub and on a fixed element for causing the blades to travel in a conical path with reference to the hub while rotating bodily therewith. 50

3. A propelling device including a hub, circumferentially spaced blades carried by and protruding from the hub, a rotary-driven shaft operatively connected with the hub for imparting rotational movement to the hub and turning of 55 the blades therewith around the axis of the shaft and coaxing means for causing the blades to travel in conical paths with reference to the hub while rotating therewith.

4. A propelling device including a hub, circumferentially spaced blades carried by and protruding from the hub, a rotary driven shaft operatively connected with the hub for imparting rotational movement to the hub and turning of the blades therewith around the axis of the shaft 65 and coaxing means for causing the blades to travel in conical paths on axes perpendicular to the axes of rotation of the shaft and hub and with reference to the hub while bodily rotating therewith. 70

5. A propelling device including a driven rotary shaft, blades carried by the shaft for bodily rotational movement therewith, and means operable by rotation of the shaft for imparting an orbital movement of the blades with reference 75

- to the shaft while the blades are rotating bodily therewith.
6. A propelling device including a driven rotary shaft, blades carried by the shaft for bodily turning movement in a circular path with and about the shaft, and means for causing the blades to move in a gyratory path with reference to the shaft and on axes perpendicular to the axis of the shaft.
7. A propelling device including a driven rotary shaft, a plurality of blades carried by the shaft for limited universal rocking movement with reference thereto and protruding from the shaft in generally radial directions, and means operable by rotation of the shaft for causing the blades to turn with and annularly around the axis of the shaft and for causing said blades each to move around an axis perpendicular to the axis of the shaft and at an angle to said perpendicular axis.
8. A propelling device including a driven rotary shaft, a blade supporting unit mounted on the shaft for limited universal rocking movement with reference thereto, blades carried by said unit extending therefrom in generally radial directions with reference to the axis of the shaft and means operable by rotation of the shaft for causing the blades to turn with and annularly around the axis of the shaft and for causing the same to each move in a conical path around an axis perpendicular to the axis of the shaft.
9. A propelling device including a driven rotary shaft, a blade supporting unit comprising a spherical central portion and radial socketed arms, and means for mounting said unit for limited universal rocking movement with reference to the shaft, blades having shanks mounted and secured in said arms and means operable by rotation of the shaft for causing the blade supporting unit and blades to turn with and annularly around the axis of the shaft and for causing said blades each to move in a conical path around an axis perpendicular to the axis of the shaft.
10. A propelling device including a driven rotary shaft, a blade supporting unit comprising a spherical central portion and radial socketed arms, and means for mounting said unit for limited universal rocking movement with reference to the shaft, blades having shanks mounted and secured in said arms and means operable by rotation of the shaft for causing the blade supporting unit and blades to turn with and annularly around the axis of the shaft and for causing said blades each to move around an axis perpendicular to the axis of the shaft and at an angle to said perpendicular axis.
11. A propelling device including a driven rotary shaft, a plurality of blades carried by the shaft for limited universal rocking movement with reference thereto and protruding in a generally radial direction therefrom, a hub secured to said shaft for rotation therewith, means located in the hub and operably connected with the blades for causing the same to turn with and annularly around the axis of the shaft and for causing said blades to each move around an axis perpendicular to the shaft axis.
12. A propelling device including a driven rotary shaft, a hub secured to the shaft for rotation therewith, a gear concentric to and fixed with reference to the shaft and the axis of rotation of the hub, circumferentially spaced blades protruding in a generally radial direction through the hub, an eccentric for each blade mounted to turn in the hub on radial axes perpendicular to the axis of rotation of the shaft and hub, and planetary gears meshing with the fixed gear and connected with the eccentrics for turning the same upon rotation of the shaft and hub.
13. A propelling device including a rotary driven shaft, blades for bodily turning therewith annularly around the axis of the shaft and means for imparting an orbital movement to the blades around an axis perpendicular to the shaft axis while turning with the shaft.
14. A propelling device including a blade having a shank at the inner end thereof, means for mounting the free inner terminal of the shank for universal movement, and an eccentric spaced from said inner terminal of the shank for imparting motion to the blade to cause the same to travel in a conical path.

EARL Houser Smith.
